J. F. RHOADES.

ABSORBING, CONDENSING, AND PURIFYING APPARATUS.

APPLICATION FILED DEC. 17, 1914.

1,171,648.

Patented Feb. 15, 1916.

UNITED STATES PATENT OFFICE.

JOHN F. RHOADES, OF MILLINOCKET, MAINE.

ABSORBING, CONDENSING, AND PURIFYING APPARATUS.

1,171,648.

Specification of Letters Patent. Patented Feb. 15, 1916.

Application filed December 17, 1914. Serial No. 877,757.

To all whom it may concern:

Be it known that I, JOHN F. RHOADES, a citizen of the United States, residing at Millinocket, in the county of Penobscot and State of Maine, have invented certain new and useful Improvements in Absorbing, Condensing, and Purifying Apparatus; and I do hereby declare the following to be a full, clear, and exact description of the invention, such as will enable others skilled in the art to which it appertains to make and use the same.

My invention relates to improvements in apparatus for absorbing, condensing and purifying liquids or gases and resides in the provision of such apparatus that is particularly designed for making sulfuric acid (H_2SO_4) by an intermittent process but may be used for such purposes as "scrubbing" gas or for condensing or other purifying purposes.

Another object of my invention is to provide apparatus that is built up of a number of units, each unit being capable of independent use and constructed to operate in conjunction with any number of similar units dependent upon the character of use of the apparatus as a whole.

Another object is to provide simply constructed apparatus that may be operated at an extremely low cost for various absorbing, purifying and condensing purposes and which will prove extremely effective in use.

The above and additional objects are accomplished by such means as are illustrated in the accompanying drawings, described in the following specification and then more particularly pointed out in the claims.

With reference to the drawings, wherein I have illustrated the preferred embodiment of my invention as it is reduced to practice, and throughout the several views of which similar reference numerals designate corresponding parts, Figure 1 is a view partly in elevation and in section of my improved apparatus, and Fig. 2 is a detail view of one of the strainers.

Referring to the drawings by characters of reference A and B designate similar units of construction that are operatively associated with one another and a storage unit C. I have illustrated two units connected with the storage unit forming a complete plant

but it is to be understood that any number of units may be connected with one another and the storage unit C or a single unit used if desired. In view of the fact that both the units illustrated are similar as to construction, it is thought necessary to describe only one of them, the one A being chosen.

The unit A comprises a closed upper tank 1 that is formed with a frusto-conical bottom wall 2 and is connected by a vertical suction pipe 3, to a lower closed tank 4. The pipe 3 is extended well into the tank 4 and establishes a communication between the tanks 2 and 4. The lower end of the tank 4 is formed of frusto-conical shape as at 5 and a pipe 6 leads from the lower end 5 of the tank 4 to a suction pump designated 7 as an entirety. A base or support 8 is provided for the pump 7. Leading from the pump 7 to the tank 1 is a vertical return pipe 9 that at its upper end is communicated with a discharge pipe 10 which extends through the upper end of the tank 1 into the tank upon one side thereof.

I provide a gas or vapor pipe 11 that is disposed above the tank 2 and is provided with a downwardly directed end 12 which is connected to and communicates with the tank 2.

A cut out valve 13 is mounted in the pipe 9 adjacent to its lower end and a similar valve 14 is connected with the pipe 3 adjacent to its lower end but at a point above the tank 4.

An overflow pipe 15 is connected at its ends with the upper end of the tank 4 and with the tank 1. The pipe 15 extends upwardly through the bottom wall of and into the tank 1 and terminates at a point above the normal liquid level thereof, as shown in the drawings. A gas outlet pipe 16 is extended through the top wall of the tank 4 to a point well within the tank and is connected with another unit, for example the unit B when more than one unit is used to make up a plant.

The tank 4 is considerably larger than tank 1 and has mounted therein an inverted container of preferably cylindrical form 17. The container 17 is held by suitable supporting brackets 18 in circumferential spaced relation to the tank 4 and is spaced from the ends of the tank. The upper end of the container is closed while the lower is open and the pipe 3 extends through the

upper closed end of the container and terminates approximately centrally within the container. The lower end of the pipe 3 is flared as at 19 for a purpose to be later more fully described. A baffle plate 20 is secured within the container 17 by means of suitable brackets 21 and is spaced at its periphery from the walls of the container, said baffle plate being disposed in a horizontal plane and being preferably of circular formation. The periphery of the baffle plate is upturned as at 22 and a central deflecting ridge or upwardly extending portion 23 is provided and disposed directly beneath and in alinement with the lower end of the pipe 3.

In using one of the units of my apparatus for making sulfurous acid the tanks are filled with water. The pipe 11 is suitably connected with a sulfur burning furnace or retort, not shown, so that the fumes or gas caused by the combustion of the sulfur is directed to the upper tank 1. The pump 7 is caused to operate by any suitable means, not shown, so that the liquid within the tank 4 is drawn therefrom and forced upwardly through the pipe 9 into the tank 1. The liquid falling into the tank 1 rapidly flows downwardly through the pipe 3 and in so doing with such rapidity causes the sulfur gas to be drawn downwardly through the pipe 3 into the container 17. Gas discharging from the flared end 19 of the pipe 3 against the baffle plate in the form of bubbles is caused to break and become absorbed by the liquid. The unabsorbed gas passes upwardly through the pipe 16 and is conducted to another unit of the apparatus, for example the one B. In order to break up the gas bubbles I provide a number of breakers 24 that comprise foraminous strips placed within the pipe 3 at spaced points therein. The gas drawn downwardly by the water flowing through the pipe 3 in the form of bubbles is caused to be absorbed by the liquid as the bubbles encounter the breakers 24.

To provide for the gas being drawn into the pipe 3, a plurality of suction tubes 25 are supported in a vertical plane within the tank 1 by a circular supporting plate 26. The plate 26 is supported by a suitable arm 27 in spaced relation to the bottom wall 2 and above the point of communication with the pipe 3. The tubes 25 extend through the plate and are arranged to discharge into the pipe 3, the upper ends of the tubes being arranged above the normal liquid level of the tank 1. A frusto-conical mixing chamber 28 is secured to the wall 2 of the tank 1 and connects the pipe 3 with said tank. It will thus be seen that the down rush of liquid to the chamber 28 into the pipe 3 will cause a suction to be produced in the pipes 25 and the gas or fumes to be drawn through the tubes 25 into the chamber 28

from whence it will be conducted downwardly through the pipe 3 into the container 17.

It will be readily seen that with a single unit of the apparatus liquid may be continuously sulfurized and absorption of the gases is had.

When two units are connected with the storage system as shown in Fig. 1 of the drawings; the unit B which is provided with a gas discharge pipe 29 that is similar to the one 16 is connected with the unit A by means of the horizontal connecting pipe 30 which is connected at its ends with the pipes 16 and 29.

The storage unit C comprises an elongated vertically arranged tank 31 that is considerably larger than the tanks 4. The tank 32, similar to the tanks of the units A and B is arranged above the tank 31 and connected therewith by means of a pipe 33. The pipe 33 extends downwardly into the tank 31 and terminates at a point adjacent to the lower end of said tank. The pipe 33 is connected with the tank 32 by means of a mixing chamber element 34 that is similar to the one 28 and a baffle plate 35 is mounted within the tank 31 and disposed below the discharge end of the pipe 33. A pump 36 is provided for the storage unit and is connected with the tank 31 by means of a pipe 37. A pipe 38 is connected with the pump 36 and upper tank 32 of the storage unit and is identical with the pipe 9 of the unit A. An overflow pipe 39 is provided for the tanks 31 and 32 of the storage unit C. This pipe 39 operates in the same manner as does the one 15. A vent or air escape pipe 40 is connected with the tank 31 at the upper end thereof. A branch pipe 41 connects the pipe 30 with the tank 32. Thus it will be seen that the unabsorbed gases in leaving the tanks 4 of the units A and B is conducted by means of the pipes 30 and 41 into the tank 32 of the unit C and will be drawn into storage tank 31 by the action of falling liquid in the pipe 33 similarly to the operation of the unit A. Pipes 42 and 43 connect the tanks 4 of the units A and B with the tank 31 of the unit C at points adjacent the lower ends of said tanks and valves 44 are mounted in the pipes 42 and 43. The partly finished product that is contained within the tank 31 of the unit C is drained or allowed to flow into the tank 4 of the units A and B through the pipes 42 and 43. The finished product is discharged at 46. By means of the pump 36 the liquid within the tank 31 is set circulating and in so doing absorbs the gases which have been heretofore unabsorbed by the units A and B. A horizontal connecting pipe 45 is connected with the pipes 9 of the units A and B and leading from the pipe 45 at a point intermediate the ends thereof is a discharge pipe 46. Valves 47 and 48 are

arranged in the pipe 45 on opposite sides of the discharge pipe 46 and control the flow of finished product from the units A and B respectively.

5 With reference to the foregoing description it will be seen that with my improved apparatus that the sulfur fumes will be absorbed readily by the solution kept circulating in the several units of the apparatus and 10 sulfuric acid made.

My apparatus may be utilized for "scrubbing" gases so as to purify them as will be readily observed and for condensing purposes if desired.

15 The tanks 4 of the units A and B may be kept supplied with the desired solution when the device is used for making sulfuric acid by the tank 31 of the storage unit C. The tank 31 is considerably larger and is arranged above the tanks 4.

20 In practice, I have found that the form of my invention, illustrated in the drawings and referred to in the above description, as the preferred embodiment, is the most efficient and practical; yet realizing that the 25 conditions concurrent with the adoption of my device will necessarily vary, I desire to emphasize the fact that various minor changes in details of construction, proportion and arrangement of parts may be resorted to, when required, without sacrificing any of the advantages of my invention, as 30 claimed.

What is claimed is:—

35 1. In an absorbing, condensing, and purifying apparatus, an upper closed tank, a closed tank arranged below the upper tank, a pipe communicating the tanks with one another, a gas feed pipe communicating 40 with the upper tank and means to draw a liquid placed in the lower tank therefrom and conduct it to the upper tank whereby it will drop back into the lower tank through the pipe connecting the tanks.

45 2. In an absorbing, condensing and purifying apparatus, a storage tank, a plurality of closed upper tanks arranged above the plane of the storage tank, a plurality of closed lower tanks, means to establish a 50 communication between the lower and storage tanks, vertical pipes connecting the lower tanks with some of the upper tanks, means for connecting the storage tank with one of the upper tanks, a gas pipe communicating with the upper tanks that are connected to the said lower tanks and means for connecting the lower tanks and the stor- 55

age tank with their respective upper tanks to draw a liquid from the lower and storage tanks and deposit it into the upper tanks. 60

3. In an absorbing, condensing, and purifying apparatus, a closed tank, an inverted container within said closed tank being spaced circumferentially therefrom, a closed tank arranged above said first tank, a pipe 65 arranged vertically and communicating said tanks with one another, a gas feed pipe communicating with the upper tank, a gas outlet pipe extending through the lower tank and communicating with the inverted 70 container, said first named connecting pipe extending through the upper closed wall of the container and arranged to discharge into said container, a baffle plate arranged below the discharge end of said first named 75 connecting pipe and within said inverted container, and a gas outlet pipe extending within said container and arranged for communication with the upper tank.

4. In an absorbing, condensing and purifying apparatus, tanks arranged one above the other, a pipe connecting the tanks, means for forcing the liquid from the lower tank upwardly into the upper tank whereby it will drain by force of gravity from the 85 upper tank back into the lower tank, a gas or vapor inlet pipe connected with the upper tank whereby the gas is drawn downwardly by water flowing back into the lower tank from the upper tank, a second set of 90 tanks, means to circulate liquid contained in the tanks and means carried by the first tank for conducting the unabsorbed gas or vapor in the lower of the first tanks to the upper of the second set of tanks. 95

5. An absorbing, condensing and purifying apparatus including a storage tank, a plurality of closed upper tanks, a plurality of closed lower tanks, means to establish a communication between the lower tanks 100 and some of the upper tanks and between the storage tank and one of the upper tanks, a gas pipe communicating with those of the upper tanks that are connected to the lower tanks, an overflow pipe connecting 105 the upper tank with the lower and storage tanks.

In testimony whereof I affix my signature in presence of two witnesses.

JOHN F. RHOADES.
